CALEB E. SUMMERS, OF PONTIAC, MICHIGAN, ASSIGNOR TO GENERAL MOTORS CORPORATION, OF DETROIT, MICHIGAN, A CORPORATION OF DELAWARE

MEANS TO PREVENT VALVES FROM STICKING

Application filed March 31, 1928. Serial No. 266,282.

This invention relates to an internal combustion engine and more particularly to an exhaust valve.

One of the defects of poppet valves is the tendency, under certain conditions, of the exhaust valve stems to stick in their guides to such an extent that the valve spring pressure is insufficient to close the valves.

Observation indicates that in a majority 10 of cases, valve sticking is due to oil which works up between the valve stem and its guide and at some point between the top and bottom of the guide, is subjected to a temperature high enough to decompose or carbonize the oil. The accumulation and hardening of the material thus produced causes the valve to stick.

It is an object of the present invention to prevent the sticking of the valve stems by 20 preventing the oil from working up along the valve stems to a point where the temperature is sufficiently high to cause decomposition of the oil. In this connection it may be taken as obvious that the ordinary exhaust 25 valve stem is hottest in the region adjacent the head and becomes gradually cooler toward the other end.

Other objects and advantages of the invention will appear in the course of the following description, taken in connection with the accompanying drawing and appended claims.

In the drawing:

Figure 1 is a transverse vertical section with parts broken away, taken through a portion of an internal combustion engine embodying my invention.

Figure 2 is an enlarged side view of the 40 valve stem guide shown in Figure 1.

Figure 3 is a section on the line 3-3 of Figure 2.

Figure 4 is a view similar to Figure 1 but showing a modified form of my invention.

Figure 5 is a view similar to Figure 1 and showing another modification of my invention.

Referring to the drawing, I have illustrated in Figure 1 a portion of an internal 50 combustion engine including an engine block

6 and cylinder head 8. The engine block, which is of conventional construction, includes a cylinder wall 10 and water jacket 12, and an exhaust port 14 connected with the combustion chamber 18 in the cylinder head 55 by an opening formed with a valve seat 16. Rigidly fixed in an opening in a web 20 of the engine block is a vertically disposed bearing sleeve 22.

Slidable in the bearing sleeve 22 is a valve 60 stem 24 provided on its upper end with a valve head 26 adapted to seat on the valve seat 16. The lower end of the stem carries a washer 40, and surrounding the stem between the washer 40 and the web 20 is the usual 65 valve spring 42 for holding the valve seated. The valve stem may be lifted in any usual or suitable manner, as by a cam shaft 11 and tappet 30.

Just underneath the web 20 the bearing 70 sleeve 22 is provided with a lateral recess or chamber 46. This recess may be produced by drilling a hole through the wall of the sleeve, as shown in Figure 3, the bore of the recess being slightly larger than the internal diameter 75 of the bearing sleeve so that a circular pocket or open space is left about the inner surface of the bearing sleeve, opening out through the side of the sleeve.

This clearance interrupts or breaks the continuity of the sliding or bearing surface entirely around the periphery of the valve stem and affords an annular pocket or recess into which any oil carried upward on the valve 80 stem during valve movement enters and is collected for return to the tappet chamber. Since the clearance space completely surrounds the valve stem, the likelihood of oil being pumped to a point of high heating is materially reduced, if not entirely eliminated. 85

With the structure described it will be noted that water circulates in the cooling jacket about the web 20 and at all times prevents overheating of the valve stem and bearing sleeve within and below the web 20. In the normal operation of the engine, lubricating oil gathers upon the lower end of the stem and works upward to the region of opening 46. Since the pressure within the exhaust port 14 is constantly changing and is fre- 95 100

quently above atmospheric pressure while the engine is running, there may at times be a slight leakage of exhaust gases along the valve stem 24 and this will be sufficient to prevent the rise of oil past the opening 46 and will also cause any excess oil to pass out through this opening. The upper portion of the sleeve 22 may be lubricated if desired with any heat resistant lubricant, such as graphite.

In Figure 4 I have illustrated a slightly modified form of my invention in which a bearing sleeve 23 supported in the web 20 is provided on its inner surface with an annular groove 50, and with a port 52 through the bearing sleeve in the lower part of the groove. It will be apparent that during the lifting movement of the valve off its seat there will be a tendency for the lubricating oil film carried by the valve stem to work up on the contacting surface of the guide until the contact is broken by the annular groove 50 where the oil is collected and returned to the tappet chamber. A part of this oil may still cling to that part of the stem moved into the groove and beyond the lower guide surface, and to prevent its being deposited on the upper guide surface beyond the groove it is desirable that the size of groove 50, taken axially of the valve stem, be slightly greater than the valve lift so that that part of the stem which contacts with the lower guide surface when the valve is seated may move into the groove when the valve is unseated, but will at no time move far enough to contact with the upper guide surface and thus the oil thereon will not be carried past the groove 50.

In the modification shown in Figure 5, a bearing sleeve 60 is fixed in web 20 and is formed with a bearing surface which is reduced at its lower end. Journaled in the bearing is a valve stem comprising an upper portion 62 and a reduced lower end 54. An opening 55 is formed in the side of the bearing sleeve at the top of the reduced portion of the bearing, it being noted that the reduced end 54 of the valve stem extends some distance above the opening 55, this arrangement providing an annular chamber between the valve stem and bearing. The embodiment illustrated in this view is otherwise the same as that described above.

I claim:

1. Means to prevent gumming of lubricant on the bearing surfaces of valve parts of an internal combustion engine or the like, including in combination, a valve tappet chamber, a valve stem guide bushing projecting thru a wall of said chamber, and having a transverse opening of a diameter greater than that of the bore of the bushing drilled thru the side thereof and located below said wall to provide a space in direct communication with said tappet chamber, and a valve stem slidable in said bushing.

2. Means to prevent gumming of lubricant

on the bearing surfaces of valve parts of an internal combustion engine or the like, including in combination, a valve tappet chamber, a valve stem guide bushing projecting into said chamber and thru a wall thereof, and having below the wall, a lateral opening entering the bore thereof and being of larger diameter than the bore, to provide an interior annular recess in direct communication with the tappet chamber, and a reciprocating valve stem mounted in said bushing.

3. Means to prevent gumming of lubricant on the bearing surfaces of valve parts of an internal combustion engine or the like, including in combination a valve tappet chamber, a valve stem guide bushing projecting into said chamber thru a wall thereof, and having an interior recessed portion, the wall of said bushing having an opening therethru in that portion thereof that extends into said chamber, to place the recessed portion in direct communication with the valve tappet chamber, and a valve stem reciprocably mounted in said bushing.

4. The structure of claim 3 wherein the length of the recessed portion is greater than the range of reciprocation of the valve stem.

5. Means to prevent gumming of lubricant on the bearing surfaces of valve parts of an internal combustion engine or the like including in combination, a valve tappet chamber, a valve stem guide member projecting into said chamber thru a wall thereof, and a valve stem member slidably mounted in said guide member, the adjacent surfaces of said members being spaced apart for a portion of their extent to provide clearance therebetween, and the wall of said guide member having a lateral opening in that portion projecting into the tappet chamber, leading to said clearance space, whereby said clearance space is in direct communication with said tappet chamber.

In testimony whereof I affix my signature.

CALEB E. SUMMERS.
